UNITED STATES PATENT OFFICE.

HENRY JOHNSON, OF DETROIT, MICHIGAN, ASSIGNOR OF ONE-HALF TO WOLVERINE MANUFACTURING COMPANY, A CORPORATION OF MICHIGAN.

COLLAPSIBLE LEAF FOR EXTENSION-TABLES.

SPECIFICATION forming part of Letters Patent No. 716,238, dated December 16, 1902.

Application filed April 28, 1902. Serial No. 104,986. (No model.)

To all whom it may concern:

Be it known that I, HENRY JOHNSON, a citizen of the United States, residing at Detroit, in the county of Wayne and State of Michigan, have invented certain new and useful Improvements in Collapsible Leaves for Extension-Tables, of which the following is a specification, reference being had therein to the accompanying drawings.

The invention relates to extension-tables of that general type in which the leaves when not in use are stored within the body of the table. A serious objection to tables of this type is that the leaves are necessarily of slightly less width than the body portion of the table to permit of storing therein, and thus when the table is extended an unsymmetrical appearance is produced. Various expedients have been tried to diminish the difference in width between the leaves and the table-top; but no practical construction has been devised in which an absolutely uniform width is maintained.

With the present invention the objection is entirely overcome; and the invention consists, broadly, in the construction of a leaf adapted to be collapsed so as to diminish its width and to permit of readily storing the same within the stationary portion of the table.

The invention further consists in the peculiar construction as hereinafter described and claimed.

In the drawings, Figure 1 is a perspective view of a table partly broken away to show the leaves stored therein. Fig. 2 is a plan view showing the table extended. Fig. 3 is a perspective view of one of the leaves in collapsed position. Fig. 4 is a horizontal section through the leaf, showing the construction of joint between the sections thereof. Fig. 5 is a cross-section of the table.

A is a table, which may be of any suitable construction, adapted to have the leaves stored therein when not in use. As shown, this table is provided with a round or oval top; but my improvements are equally applicable to tables of the square type.

B represents the extension-leaves. Each of these leaves is divided transversely there-

of or longitudinally of the table into two sections *a* and *b*. The joint between these sections is such that in position for use they are held in alinement with each other and form a continuous leaf extending for the full width 55 of the table. The sections are, however, capable of movement in relation to each other, so that when they are to be stored they may be moved inward, thus diminishing the width 60 of the leaf.

In the construction which is preferably employed and which is shown in the drawings the line of division between the sections *a* and *b* is inclined to the longitudinal axis of the table and the adjacent edges of said sections are slidingly joined to each other. This sliding joint may be formed, as shown, by providing the edge of one of the sections with a dovetail tenon or tongue *c*, while the edge of the opposite section is provided with a corresponding dovetail groove *d*. The two sections may be engaged with each other by sliding the tongue into the groove. When the sections are in exact alinement, the width of the leaf is extended to be equal 75 or greater than that of the table-top; but when moved into the position shown in Fig. 3 the width is diminished to permit of storing. In order to limit the amount of lateral movement of the sections in relation to each other and to prevent accidental disengagement thereof, a stop is preferably provided. This, as shown in Fig. 4, may be formed by cutting away a section of the tongue, as indicated at *e*. *f* is a pin secured in the grooved 85 section of the leaf and passing through the cut-away portion *e*. This pin is so located that it will form a stop to prevent the movement of the sections to extend the same beyond normal length. At the same time the 90 cut-away portion *e* is long enough to permit of sliding the sections in the opposite direction, so as to collapse the leaf.

In the construction shown in the drawings the leaves *B* are provided with depending 95 rail-sections *C*, which are adapted to form extensions of the side rails *D* of the table. Each section is also provided with a cleat *E*, which in the collapsed position of the leaf will lie adjacent to the slides of the table, but in the 100

extended position will rest upon said slides and will support the leaf at the exact plane of the table-top, as shown in Fig. 5. To hold the leaves in engagement with the stationary 5 table-top, they may be provided with the usual dowel-pins and sockets.

What I claim as my invention is—

1. A table-leaf formed in two sections secured together, and means whereby said sections are relatively adjustable in the same plane.

2. A table-leaf formed in two sections secured to each other and means whereby said leaves are relatively adjustable in the same 15 plane in a direction to contract or extend the width of the leaf.

3. In an extension-table, a leaf severed in an inclined line into two sections having their adjoining edges slidably secured to each 20 other for the purpose described.

4. A table-leaf comprising two complemen-

tary sections having their line of severance inclined to their rectilinear axes, and the adjoining edges of said sections being formed with an interlocking tongue-and-groove sliding engagement.

5. A table-leaf comprising two complementary sections having their line of severance inclined to their rectilinear axes, and their adjoining edges formed with an interlocking tongue-and-groove sliding engagement, a portion 30 of the tongue member being cut away, and a stop-pin secured to the grooved member and passing through said cut-away portion of said tongue.

In testimony whereof I affix my signature in presence of two witnesses.

HENRY JOHNSON.
